UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed April 27, 1925. Serial No. 26,131.

My invention relates to car couplers and particularly to the form known as the type D coupler. While the improvements hereinafter described and claimed are not limited in their application to a coupler of that specific type, they are especially designed for embodiment in a coupler of that well known form.

The principal object of the invention is to facilitate the raising of the lock lifter and the lock to a lock set position.

In the standard D-coupler the operation of moving the lock to lock set position requires the application of considerable force. Upon the initial raising of the lifter the trunnions with which the latter is provided come in contact with the upper walls of the trunnion slots in the lock and as such walls, owing to tilting of the lock, at times are disposed at a comparatively small angle to the horizontal, the sliding movement of the trunnions in the trunnion slots is correspondingly difficult. Moreover, after the trunnions of the lifter have been moved forward and upward to their extreme limit within the lock, they are still positioned off center or well to the rear of the gravity axis of the lock, and as a result the lifting of the lock to lock set position is not as readily performed as would be the case if the force for raising the lock were applied to the latter at a point nearer the vertical line passing through the center of gravity thereof. In the present invention the operation of causing the lock to assume lock set position is rendered easier of accomplishment by so constructing and relating the lifter, lock and coupler head that during the initial raising of the lifter and its movement into the lock, the lifter trunnions do not slide in contact with the top walls of the trunnion slots.

A principal feature of the invention, generally stated, consists in combining a vertically movable rearwardly swinging lock with a coupler knuckle, a lifter for actuating said lock having outwardly extending trunnions which are received in an upwardly and rearwardly opening slot in the lock, and a coupler head having a projection disposed rearwardly of said lock and adapted to engage the lower end of the lifter to prevent accidental unlocking of the lock, the lower end of the lifter being adapted during its initial unlocking movement to en-

gage and slide upon said projection so as to prevent the upper sides of the lifter trunnions from coming into sliding contact with the lock.

Other features of the invention involving special relations of parts and advantageous features of construction will hereinafter appear and be pointed out in the claims.

In the drawings illustrating my invention as applied to a master car builders standard D-coupler,

Figure 1 is a vertical sectional view of a coupler, the lock and its lifter being in elevation and the parts being in locked relation.

Figure 2 is a vertical sectional view of a portion of the mechanism shown in Fig. 1, but illustrating the lifter in the position it assumes at the end of its initial unlocking movement.

Figure 3 is a detail elevational view of a portion of the lock and lifter, the parts being in the position shown in Fig. 2.

In the drawings, 1 is the coupler head upon which the rotatable knuckle (not shown) is mounted in the usual manner. Outward rotation of the knuckle is normally restrained by means of a lock 2 having a downwardly extending leg 3 which projects through an opening 4 in the lower wall of the coupler head. The lock is provided on its forward face with a lug 5 which when the lock is raised sufficiently to free the knuckle comes into contact with the coupler head and, under the influence of the upward pull upon the lock exerted by the lifter, swings rearwardly so as to effect a knuckle opening rotation of the knuckle opener 6. The knuckle opener is preferably of the standard form employed in the D-coupler, that is to say, it is a horizontally rotatable bell crank lever pivotally mounted upon the lower wall of the coupler head, one of its ends being disposed in the path of movement of the depending leg 3 of the lock and its other end extending behind the tail of the knuckle in position to communicate uncoupling rotation to the latter.

The lock 2 is provided with an upwardly and rearwardly opening slot 7 for receiving the lower end of the lifter 8. The side walls of the slot 7 are recessed as at 9 to receive 10 and permit sliding movement of the oppositely disposed trunnions 10 formed upon the lifter adjacent its lower end, the upper por-

tions of said recesses being cylindrically curved so as to permit of a relative turning or pivotal movement of the lock 2 and lifter 8 when the lifter has been fully retracted 5 into the lock. The side walls of the lifter receiving slot 7 are preferably provided with shoulders or faces 11 with which the trunnions 10 are respectively adapted to cooperate in the initial unlocking movement of 10 the lifter. The shoulders normally stand immediately in advance of the trunnions, and when the lifter executes its preliminary movement engage said trunnions so as to compel the lower end of the lifter to move 15 upwardly toward the lock down lug or projection 12 of the coupler head before it passes from beneath said lug. For a similar purpose, and as is also deemed preferable, the lifter 8 may be formed at its lower 20 end with a downwardly extending lug or shoulder 13 which, as shown in Fig. 1, overlaps the rear face of the lock 2 when the parts are in normal locked relation. By the cooperation of this lug 13 with the rear face 25 of the lock the lower end of the lifter 8 is likewise compelled to move upwardly toward the lock-to-the-lock projection 12 of the coupler head before it can be retracted into the slot of the lock 2.

30 At its lower end the lifter 8 has an upwardly facing shoulder 14 which normally stands beneath the lock down lug 12 in spaced relation thereto. If the lock 2 attempts accidentally to move to unlocked position the shoulder 14, functioning in a well known manner, comes into contact with the lower face of the lug 12 and arrests said accidental unlocking movement.

When in normal locked relation the shoulder 40 of the lifter is spaced from the lower end of the lock-to-the-lock projection 12 of the coupler head a distance such that the said shoulder 14 will contact the projection 12 before the trunnions 10 have been raised 45 high enough to come into engagement with the inclined upper walls 15 of the trunnion slots in the lock. The withdrawal of the lower end of the lifter into the slot 7 of the lock is thus effected while the upper surfaces 50 of the trunnions 10 are held out of contact with the top walls 15 of the trunnion slots and frictional contact between these parts is thereby avoided. In the D coupler as at present constructed the lock 2 when in 55 locked position is capable of tilting longitudinally of the coupler so that the lower wall 16 of the slot 7 and the upper walls of the trunnion slots, which are parallel thereto, at times assume inclined positions 60 varying from about 31 degrees to 40 degrees to the horizontal, while the inclined lower face 17 of the lug 12 is approximately forty degrees to the horizontal at all times. It will be appreciated, therefore, that by causing 65 the lower end of the lifter 8 to cooperate

with the under face of the lug 12 during the initial unlocking movement of the lifter, instead of relating the parts so that the trunnions 10 slide upon the inclined top walls of the trunnion slots during such movement, 70 the force required to withdraw the lifter 8 into the slot of the lock is very considerably reduced. This contact of the surface 14 of the lifter with the surface 17 of the lug continues until the lifter has been drawn 75 into the lock to practically the full extent, and as the trunnions 10 are then further forward and nearer the center of the lock than they are in the standard design, the lock may be raised to lock set position with 80 greater ease.

It is preferred that the inclined face 14 at the lower end of the lifter shall have the same inclination to the vertical as that of the end face 17 of the lock down projection 12 of the coupler head. It is also advantageous to form the top walls 15 of the trunnion slots at such an inclination as to offer, in any tilted position the locks may assume when in locked relation, no greater resistance to 90 the movement of the lifter toward its lock-lifting position than would result from the sliding of the lifter on the surface 17 of the lock down projection 12 of the coupler head; for if, as the result of wear, or because of 95 castings not being to gauge, or for any other reason, the trunnions 10 should come into sliding contact with the walls 15 of the lock, the inclination of said walls ensure easy action even under such circumstances.

As shown in the drawings, the lower wall 16 of the slot 7 may be less steeply inclined than are the upper walls 15 of the trunnion slots, preferably having the same inclination as it now has in the standard D coupler.

I claim:

1. In a car coupler, the combination with a coupler head, knuckle, a knuckle opening lever, and a vertically movable lock for said knuckle adapted to swing rearwardly so as to engage and actuate said knuckle opening lever, of a lifter for actuating said lock, said head being provided rearwardly of said lock with a projection having an inclined face adapted to engage the lower end of said lifter to prevent accidental unlocking of said lock, said lifter being provided with oppositely extending trunnions and its lower end being adapted to stand beneath said projection when said lock and lifter are in normal locked relation, said lock being provided at its upper end with an upwardly and rearwardly opening slot whose side walls are formed with recesses to receive said trunnions, the upper walls of said recesses when the lock is in normal locked position being more steeply inclined than said inclined face of said projection, said lifter being slidably and rotatably movable in said slot and being adapted when performing an unlocking op- 125

eration to execute a preliminary movement with respect to said lock causing the lower end of said lifter to be withdrawn from beneath said projection, and the lower end of 5 said lifter being adapted to engage and slide upon said projection during said preliminary movement while said trunnions are out of contact with the upper walls of said recesses.

- 10 2. In a car coupler, the combination with a coupler head, knuckle, knuckle opening lever, and a gravity actuated lock for said knuckle adapted to swing rearwardly so as to engage and operate said knuckle opening 15 lever, of a lifter for actuating said lock, said head being provided rearwardly of said lock with a projection having an inclined face adapted to engage the lower end of said lifter to prevent accidental unlocking of said lock, 20 said lifter being provided with oppositely extending trunnions and its lower end being adapted to stand beneath and in spaced relation to said inclined face when the lock and lifter are in normal locked relation, said lock 25 being provided at its upper end with an upwardly and rearwardly opening slot whose side walls are formed with recesses to receive said trunnions, the upper walls of said recesses when the lock is in normal locked position 30 being more steeply inclined than said inclined face of said projection, said lifter being slidably and rotatably movable in said slot and being adapted when performing an unlocking operation to execute a preliminary 35 movement with respect to said lock causing the lower end of said lifter to be withdrawn from beneath said projection, said preliminary movement being adapted to cause the lower end of said lifter to contact 40 said inclined face and to slide with respect thereto while in contact therewith and while said trunnions are in spaced relation to said upper walls.
3. In a car coupler, the combination with 45 a coupler head, knuckle, knuckle opening lever, and a vertically movable lock for said knuckle adapted to swing rearwardly so as to engage and actuate said knuckle opening lever, of a lifter for actuating said lock, said lock being provided at its upper end with an 50 upwardly and rearwardly opening slot within which said lifter is slidably and rotatably

movable, said head being provided with a projection adapted to engage the lower end of said lifter to prevent accidental unlocking 55 of said lock, said lifter being provided with oppositely extending trunnions and the side walls of the slot in said lock being formed with recesses to receive said trunnions, the upper and lower walls of said recesses being 60 inclined and said upper walls being the steeper, the lower end of said lifter being adapted to extend beneath said projection in spaced relation thereto when the lock and lifter are in normal locked positions, said lock and 65 lifter having cooperating portions adapted to cause the lower end of said lifter to move toward said projection before being withdrawn from beneath the latter when said lifter performs an unlocking operation, and 70 the lower end of said lifter being slidably in contact with the under side of said projection during the unlocking operation of said lifter while said trunnions are out of contact with said upper walls.

4. In a car coupler, the combination with a coupler head, knuckle, and a vertically movable and rearwardly swinging lock for said knuckle, of a lifter for actuating said lock, said head being provided rearwardly 80 of said lock with a projection having an inclined face adapted to engage the lower end of said lifter to prevent accidental unlocking of said lock, said lifter being provided with oppositely extending trunnions and its lower 85 end being adapted to stand beneath said inclined face when the lock and lifter are in normal locked relation, said lock being provided at its upper end with an upwardly and rearwardly opening slot having oppositely 90 disposed lateral recesses for receiving said trunnions, the upper walls of said recesses in any position the lock may assume while the parts are in locked relation being inclined to the horizontal at an acute angle not 95 less than the acute angle formed with the horizontal by the inclined face of said projection, and the lower end of said lifter being adapted to contact and slide upon the inclined face of said projection when said 100 lifter performs an unlocking operation.

In testimony whereof I affix my signature.

WILLIAM KELSO.
